UNITED STATES PATENT OFFICE.

ANTHONY J. BURNS, OF OSWEGO, NEW YORK.

AUTOMATIC ELECTRICAL RELEASE-STARTER.

No. 876,326.

Specification of Letters Patent.

Patented Jan. 14, 1908.

Application filed March 15, 1907. Serial No. 362,614.

To all whom it may concern:

Be it known that I, ANTHONY J. BURNS, a citizen of the United States, residing at Oswego, in the county of Oswego and State of New York, have invented a new and useful Automatic Electrical Release-Start; and I do hereby declare the following to be a full, clear, and exact description of the invention, such as will enable others skilled 10 in the art to which it appertains to make and use the same.

This invention pertains to an automatic release starter, adapted for use in connection with alternating current motors, for the 15 purpose of starting the same.

In connection with an apparatus of the above type, and as shown in the drawings, the invention aims as an essential and primary object to provide a device of this 20 character, whereby, in case of failure of current supply, the automatic switch of the device will be brought into operation, thereby shutting down the motors. This device will automatically, as will be understood, open the circuits, thereby obviating the necessity of the operator being in readiness to do so by hand, that is in case of failure of current supply, as above stated. When the motor circuit is open the motor 25 is dead and will remain so until the operator closes it again, thus leaving the lines open, so that the operator at the station may reestablish the current supply without danger to the machines on the circuit. This 30 device saves considerable time, which under the previous system of hand control apparatus was wasted. It has been found, as will be understood, that all motor circuits 35 should be open before sending current over 40 the lines.

This invention comprises further objects and combinations of elements which will be hereinafter more fully described, shown in the accompanying drawings, and the novel 45 features thereof will be pointed out by the appended claims.

To obtain a full and correct understanding of the details of construction, combinations of features, elements and advantages, 50 reference is to be had to the hereinafter set forth description and the accompanying drawings in connection therewith, wherein

Figure 1 is a front elevation of an apparatus of the above set forth type illustrating 55 the invention. Fig. 2 is a side elevation of the device, illustrating more clearly the con-

struction to the right of the automatic switch. Fig. 3 is a sectional view on the line 3-3 of Fig. 1, for the purpose of illustrating more clearly and diagrammatically 60 the location of the primary and secondary transformer. Fig. 4 is a detail perspective view of a portion of the automatic switch, showing the operating handle therefor. Fig. 5 is a sectional view through the 65 means for operating the oscillatory clutch 66.

Making renewed reference to the accompanying drawings, wherein similar reference characters indicate corresponding parts in 70 the several illustrations, by figures, 1 designates an iron box, in the center of which is located primary and secondary windings of the transformers *a* and *b*, which secondaries of the transformers are utilized in starting up, 75 by the operation of the hand operated switch hereinafter described, so that the current to the motors will be supplied at a low voltage, that is when the hand operated switch is thrown into coöperation with the lower set of 80 terminals 66, which are heavily fused to carry the heavy current for starting. The equivalent of the transformers, such as induction resistance, or any other substitute, may be employed, if desired. Upon the front of this 85 iron box are fixed an upper and lower set of terminals 11 and 11', which are fixed to a marble slab *c*; this marble slab closes the front of the iron box, as shown clearly in Fig. 3 of the accompanying drawings, and is secured in position by means of screws *d*, or any 90 other suitable means. The upper row of the lower set of terminals and the lower row of the upper set of terminals are electrically connected, as shown at *e*; all of these terminals are fastened to the marble slab by 95 their shank portions *f* thereof, being passed through apertures *g*, in the said slab, and securely fixed, by means of nuts 8, as clearly shown.

To coöperate with the terminals, either the upper or lower set thereof, is an automatic switch 1^a having knife blades 2, to coöperate with the lower set of terminals, and brushes 3, comprising copper strips having therebetween strips of mica, there being three of these brushes similarly constructed, which are clamped to concave portions 4 of the switch 1^a, by means of convexed strips of brass 5, and screw 6, so as to provide resiliency for the said brushes, as will be clearly evident from the drawings. This switch 100

105

110

115

comprises a shaft 7, journaled in suitable bearings 8^a, which shaft extends and rotates parallel with the face of the marble slab; projecting from this shaft is a plurality of 5 stub shafts 9, to which are secured the clamping members 10 of the concave portions 4, and of the knife blades 2 by means of screws 11^b. Surrounding the stub shafts 9 and adjacent to the inner faces of the clamping 10 members are sleeves 12, of any suitable insulating material, for the purpose of insulating the brushes and blades.

The upper ends of the stub shafts are provided with flanges 13, which are secured there- 15 to by means of screw threads 14, to prevent displacement of the sleeves.

Projecting upwardly is an operating crank arm 15, which is slightly rearwardly positioned by means of a compound curve there- 20 in; this crank arm is provided with a hand grip 16, and below this grip is an opening 17, designed to partly receive the end of the oscillatory clutch bar 18, the operation of which will be hereinafter described, which 25 end thereof is bifurcated, as at 19, to receive an anti-frictional roller bearing 20, the shaft of which is journaled in the arms 21 of the said oscillatory bar, which arms are formed by the said bifurcation. This roller bearing 30 is designed to engage the projection 22, of a cam element 23, integral or otherwise secured to the crank arm, for the purpose of holding the brushes resiliently in contact with the upper set of terminals, so as to close 35 the circuit between them. The roller bearing is held in close engagement with said projection by a spring 24, one end of which is secured to an eye 25, carried by the horizontally extending arm 26, of the oscillatory 40 clutch bar; while the other end thereof is secured to a screw 27, which is adjustably fastened to a laterally projecting lug 28, of the iron box, by means of the nuts 29, as will be clearly evident. It is equally manifest from- 45 an examination of the drawings, that the pivot 30 of the oscillatory clutch bar is of the adjustable type, thus effecting a close contact between the brushes and the upper set of terminals, and also compensating for the 50 wear upon the said brushes. This adjustable pivot is obtained by means of a plate 31 having the pivot pin 32, upon which the clutch bar is pivoted, and held thereto by any suitable means, preferably a screw 33. This 55 plate is provided with four slots 34, through which the screws 35 projecting from the side of the said iron box, extend for the purpose of holding the said plate immovable when desired.

60 The downwardly and rearwardly projecting arm 36 of the oscillatory clutch bar is guided in its movement by a bridge plate 37 securely fastened to the side of the box, as clearly shown in the drawings. This arm 36 65 is provided at its lower portion, with a hori-

zontal projecting portion 38, upon which the weight 39 falls, which weight is guided in its fall by means of the guides 40 and 41, which are secured to the side of the iron box; the guide 41 is provided with an opening 42 upon 70 its side near the top thereof for the reception of the upper end 43 of the oscillatory latch bar, which is suitably pivoted, as at 44, the operation of which latch bar will be herein- 75 after described.

The lower end of the latch bar is bent at right angles, as at 45, and is provided with an enlarged portion 46, carrying an armature 48, which is to be attracted by the magnet 49, when energized, which magnet is of the three phase type; the cam 50, at the upper end of the latch bar, will be held in the opening 42 of the guide 41, and into engagement with the friction roller bearing 51, journaled within the notch 52, of the weight 39, that is, 85 when it is in its upper position, as will be evident. When the said magnet is in an energized condition, its current is received from the generator 72 through the leads 81, as will be clearly manifest. 90

For returning the weight to its upper position it is provided with a thumb piece 53, as clearly shown. To prevent the arm 36 from being bent, at a point where it would strike the side 54 of the bridge plate 37, when oscillated by the fall of the weight, a stop 55 having a rubber covering 56 is provided, as clearly shown. The lower face of the weight is also provided with rubber 57 to obviate the jar of the sudden fall thereof, against the 100 horizontal projecting portion 38 of the arm 36, as will be understood.

When the magnet becomes deenergized through the failure of current supply, the cam 50 will be disengaged from the roller bearing 51, by contraction of the spring 58, and the said latch bar having the cam will be limited by the stop 59, as clearly shown in the drawings. One end of this spring is attached to an eye 60, of the latch bar, while the other end is fixed to an adjusting screw 61, mounted in a stud 62, which screw is rendered adjustable by means of the winged nut 63, as is clearly illustrated in the drawings. Upon two of the sides of the iron box 110 are positioned a cabinet 64, in one of which, is located the oscillatory clutch bar and the releasing means therefor, while in the other is located the hand operated switch 65, and the upper and lower co-operative terminals 66 115 therefor, which terminals and the pivot 67, for the said switch, are securely fixed to a marble slab 68, as will be apparent.

The lower row of the lower set of terminals 11' are electrically connected by the leads 69, 125 with the secondary of the transformers, while the upper row of the terminals 11' are electrically connected to the lower row of the upper set of terminals 11, as shown at e, as hereinbefore stated; the leads 71 electrically 130

connect the upper set of terminals 66 of the hand operated switch and the upper row of the terminals 11, of the automatic switch; and the transformers *a* and *b* are electrically connected to the lower row of the terminals 66 of the hand operated switch 65, by means of the leads 66^a, and the generator 72 is electrically connected through the medium of the leads 73 with the terminals 67, of the hand operated switch, which terminals 67 form the pivot for the said hand operated switch, as will be readily understood from a thorough examination of the drawings in connection with the herein description.

In event of failure of the current supply, the automatic switch will be released from engagement with the clutch bar, after which the said automatic switch will vibrate, prior to assuming a constant horizontal position, at right angles to the face of the marble slab *c*; this vibration of the automatic switch is obtained by means of the springs 75, which are wound in opposite directions about the shaft 7, each of which springs has one end thereof fixed to said shaft, while their other ends are fixed to the slab *c*, as at 76, as will be clearly manifest. The upper row of the terminals 11' are in circuit with the motor 80 and the motor generator 72, by the leads 81, as clearly shown in Fig. 1 of the accompanying drawings. The hand operated switch is of the three pole knife type having the usual fuses, and, the cabinet for inclosing said switch is lined with slate, or any other suitable material; this hand operated switch is only utilized when it becomes necessary to shut down the motor, but the automatic switch could be operated for this purpose, yet it is not good policy to do so, as there is considerable arcing, caused by opening the circuit, of an apparatus of this character, when running under load. This automatic switch is operated in two directions, first the downward, or starting position, second the upward or high voltage running position; when in the downward position, the switch blades close the circuit between the two lower sets of terminals, thereby allowing a low voltage current to pass from the secondaries of the transformers to the motor; when operated in the upward, or running position, the brushes will coöperate with the upper set of terminals 11, which will close the circuit therebetween, thereby allowing the high voltage current to pass directly from the feeders to the motor.

In starting, the hand switch is thrown to its lower position and into coöperation with the terminals 66 which are heavily fused to carry the heavy current for starting. Then the automatic switch is thrown from its neutral position to its lower position and into coöperation with the terminals 11', the motor is then receiving current at low voltage from the secondaries of the transformers. When

the hand operated switch and the automatic switch are in engagement with the lower set of terminals 66 and 11', current leaves the generator 72 through the leads 73 to the terminals 67, of the hand operated switch, through the blades thereof and the lower set of terminals 66, then the current advances through the transformers, through the medium of the leads 66^a, and through the leads 69 to the lower set of terminals 11', through the blades 2 of the automatic switch, that is to say, when in its lower position, to and through the upper set of terminals 11', thus advancing on to the three phase motor 80, through the leads 81, as will be readily traced from the drawings. This current when the two switches are in their lower position, is flowing in rapid succession, through one lead and then the other, and then back again through one of them that is not utilized for the advancing current; it will be readily observed, from the above, that the motor 80 is receiving current at a low voltage from the secondaries of the transformers. After the motor has started both hand and automatic switches are lifted to their upper position and into coöperation with the upper set of terminals, and while in this position the motor or generator is thrown directly across the line, thereby cutting the transformers out of circuit. When the automatic switch is thrown into coöperation with the terminals 11 it is held in close contact therewith, by the clutch bar, until released by the releasing mechanism, which is operated through the failure of current supply. When the hand operated and automatic switches are in their upper positions, as shown in Fig. 1 of the drawings, current leaves the generator, advancing through the leads 73, that is, alternately through one and then the other, to the terminals 67, through the blades of the switch 65 and through the upper set of terminals 66, to the upper set of terminals 11, through the medium of the leads 71, and then the current advances on through to the upper set of terminals 11', through the brushes 3 and the metallic electrical connections *e*, upon the back of the marble slab *c*, then the current continues on to the motor, through the leads 81, as will be clearly manifest. This current is also flowing in rapid succession, as when the said switches are in their lower positions; thus it will be seen, when tracing this last-mentioned flow of current, that the transformers are cut out of the circuit, and the motor and generator are thrown directly across the line, thereby generating a high voltage current. This failure of current supply may be either caused by a breakage along the line, or by throwing the hand operated switch to a horizontal or neutral position, as will be manifest.

It is to be understood that various changes and modifications may be employed in the

construction and embodiment thereof, combinations of features, and elements, without in any way departing from the spirit and scope of the invention covered by the claims 5 thereof; it being understood that whatever variations or modifications are employed must fall within the scope of the appended claims.

From the foregoing, the essential features, 10 elements and the operation of the device, together with the simplicity thereof, will be clearly apparent.

Having thus fully described the invention, what is claimed as new and useful by the 15 protection of Letters Patent, is:—

1. In an automatic release or no voltage starter, an automatic switch, terminals therefor, an oscillatory clutch bar to coöperate with said switch, and a vertically movable member for actuating the clutch bar and an electrically controlled latch bar for supporting said member.

2. In an automatic release starter, an automatic switch, terminals therefor, an adjustable oscillatory clutch bar, releasing means therefor, and electrical operated means for controlling said releasing means.

3. In an automatic release starter, an automatic switch, terminals therefor, adjustable means for holding said automatic switch in close contact with its upper set of terminals, a vertically movable member for releasing said adjustable means, an electrically controlled latch bar for releasing said member through the failure of current supply.

4. In an automatic release starter, an automatic switch, knife blades and brushes carried by said switch, an upper and lower set of terminals therefor, adjustable means for holding said brushes in close engagement with the upper set of terminals, and means for releasing said adjustable means.

5. In an automatic release starter, a switch, an adjustable lever controlling the same, and a movable member controllable by the current supply and adapted to be released by failure thereof to actuate said lever to release the switch.

6. In an automatic release starter, a switch, a lever controlling the same, and a gravitating member controllable by the current supply and adapted to be released by failure thereof to actuate said lever to release the switch and vertical guides for the gravitating member.

7. In an automatic release starter, a switch, an adjustable lever controlling the same, and a gravitating member controllable by the current supply and adapted to be released by failure thereof to actuate said lever to release the switch.

8. In an automatic release starter, a switch, an adjustable pivoted lever controlling the same, and a gravitating mem-

ber controllable by the current supply and adapted to be released by failure thereof to actuate said lever to release the switch.

9. In an automatic release starter, an automatic switch, an adjustable pivoted clutch bar controlling the same, and a movable member controllable by the current supply and adapted to be released by failure thereof to actuate said pivoted clutch bar vertical guides for the movable member.

10. In an automatic release starter, an automatic switch, an adjustable pivoted clutch bar controlling the same, and a movable member controllable by the current supply.

11. In an automatic release starter, an automatic switch, an adjustable pivoted clutch bar controlling the same, and a gravitating member controllable by the current supply and adapted to be released by failure thereof to actuate said clutch bar to release the switch.

12. In an automatic release starter, an automatic switch, an adjustable clutch bar controlling the same, and a gravitating member controllable by the current supply.

13. In an automatic release starter, an automatic switch, an adjustable pivoted means controlling the same, and a gravitating member controllable by the current supply and adapted to be released by failure thereof to actuate said adjustable pivoted means.

14. In an automatic release starter, an automatic switch, an adjustable pivoted means controlling the same, and a gravitating member controllable by the current supply.

15. In an automatic release starter, an automatic switch having knife blades and brushes, an upper and lower set of terminals therefor, an adjustable clutch bar controlling the switch, and a gravitating member controllable by the current supply and adapted to be released by failure thereof to actuate said clutch bar.

16. In an automatic release starter, an automatic switch having knife blades and brushes, an upper and lower set of terminals therefor, an adjustable pivoted clutch bar for holding said brushes in close engagement with the upper set of terminals, a gravitating member, a spring actuated latch bar for supporting said gravitating member and controllable by the current supply.

17. In an automatic release starter, an automatic switch having knife blades and brushes, an upper and lower set of terminals therefor, an adjustable pivoted clutch bar for holding said brushes in close engagement with the upper set of terminals, a gravitating member, a spring actuated latch bar for supporting said gravitating member and controllable by the current supply and adapted

to be released by failure thereof to actuate said clutch bar.

18. In an automatic release starter, an automatic switch, having knife blades and 5 brushes, an upper and lower set of terminals therefor, an adjustable pivoted clutch bar for holding said brushes in close engagement with the upper set of terminals, a movable member, guides therefor, a spring actuated 10 latch bar for supporting said movable member and controllable by the current supply and adapted to be released by failure thereof to actuate said clutch bar.

19. In an automatic release starter, an 15 automatic switch having knife blades and brushes, an upper and lower set of terminals therefor, said switch having an upwardly extending arm, said arm having a cam forming a catch, an adjustable pivoted clutch bar designed 20 to engage said catch through coöperation of the cam for holding said brushes in close engagement with the upper set of terminals, a movable member, guides therefor, said movable member being controllable by 25 the current supply and adapted to be released by failure thereof to actuate said clutch bar.

20. In an automatic release starter, an 30 automatic switch having knife blades and brushes, an upper and lower set of terminals therefor, said switch having an upwardly extending arm, said arm having a cam forming a catch, an adjustable pivoted clutch bar designed 35 to engage said catch through coöperation of the cam for holding said brushes in close engagement with the upper set of terminals, a movable member, guides therefor, a spring actuated latch bar for supporting said movable member and controllable by 40 the current supply and adapted to be released by failure thereof to actuate said clutch bar.

21. In an automatic release starter, an 45 automatic switch, a spring actuated adjustable pivoted clutch bar for controlling the same, a movable member controllable by the current supply to be released by failure thereof to actuate said clutch bar.

22. In an automatic release starter, an 50 automatic switch having an upwardly extending arm, said arm having a cam forming a catch, a spring returned adjustable pivoted clutch bar designed to engage said catch for controlling the same, a movable member controllable 55 by the current supply and adapted to be released by failure thereof to actuate said clutch bar.

23. In an automatic release starter, an 60 automatic switch having an upwardly extending arm, an oscillatory spring returned clutch bar, said arm having means to be engaged by said clutch bar and an independent gravitating member controllable by the current supply and adapted to be released by 65 failure thereof to actuate said clutch bar.

24. In an automatic release starter, an automatic switch having an upwardly extending arm, an adjustable pivoted spring returned clutch bar, said arm having means to be engaged by said clutch bar, a gravitating member controllable by the current supply and adapted to be released by failure thereof to actuate said clutch bar. 70

25. In an automatic release starter, an automatic switch having an upwardly extending arm, an adjustable spring returned clutch bar, said arm having means to be engaged by said clutch bar, a gravitating member, guides therefor, a pivoted supporting latch bar to support said gravitating member, said latch bar having an armature at its lower end, a magnet controllable by the current supply for controlling said latch bar, through the failure of which current supply the magnet will be controlled for releasing 80 the pivoted latch bar. 75

26. In an automatic release starter, an automatic switch comprising a shaft having a plurality of stud shafts, knife blades and brushes carried by said stud shafts, said 85 automatic switch having an upwardly extending arm, an adjustable pivoted spring returned clutch bar, said arm having a cam forming a catch device to coöperate with said clutch bar, a movable member, guides 90 therefor, a pivoted latch bar for supporting said movable member, an armature carried at the lower end of said latch bar, a magnet controllable by the current supply for attracting 95 said armature for controlling said pivoted latch bar through the failure of which current supply the magnet will be deenergized thereby releasing the pivoted latch bar. 100

27. In an automatic release starter, an 105 automatic switch comprising a shaft having a plurality of stud shafts, knife blades and brushes carried by said stud shafts, said automatic switch having an upwardly extending arm, an adjustable pivoted spring 110 returned clutch bar, said arm having a cam forming a catch device to coöperate with said clutch bar, a movable member, guides therefor, a pivoted spring returned latch bar for supporting said movable member, an 115 armature carried at the lower end of said latch bar, a magnet controllable by the current supply for attracting said armature for controlling said pivoted spring returned latch bar through the failure of which current supply the magnet will be deenergized 120 thereby releasing the pivoted latch bar. 120

28. In an automatic release starter, an 125 automatic switch comprising a shaft having a plurality of stud shafts, knife blades and brushes carried by said stud shafts, an upper and lower set of terminals to coöperate with said knife blades and brushes, said switch having an upwardly extending arm, a pivoted spring returned clutch bar, said arm 130

having a cam forming a catch to coöperate with said clutch bar, a gravitating member, guides therefor, a pivoted latch bar spring returned for supporting the said gravitating member, an armature carried at the lower end of said latch bar, a magnet controllable through the current supply for attracting said armature for controlling said pivoted latch bar through the failure of which current supply said magnet will be deenergized thus releasing said latch bar, a generator in circuit with said automatic starter and primary and secondary transformers in the circuit of said generator and automatic 15 starter for decreasing and increasing the voltage thereof.

29. In an automatic release mechanism, an automatic switch, a pivoted clutch bar, controlling the same, and an independent 20 movable non-pivoted member controllable by the current supply.

30. In an automatic release mechanism, an automatic switch, a pivoted clutch bar, controlling the same, an independent movable member controlled by the current supply, and guides for the said member.

31. In an automatic release mechanism, an automatic switch, terminals therefor, means for controlling the same, and means 30 movable by itself for releasing the first-named means, and a pivoted latch bar controllable by the current supply for controlling said movable means.

32. In an automatic release mechanism, 35 an automatic switch, adjustable pivoted means for controlling the same, and inde-

pendently guided means for releasing the said first-named means.

33. In an automatic release mechanism, an automatic switch, adjustable means for 40 controlling the same, and independently guided means for releasing the said first-named means, said independently guided means being controlled by current supply and adapted to be released through the 45 failure thereof.

34. In an automatic release mechanism, an automatic switch, adjustable means for controlling the same, and independently guided means for releasing said adjustable 50 means.

35. In an automatic release mechanism, an automatic switch, adjustable means for controlling the same, an independently movable member for releasing said adjustable 55 means, an electrically controlled latch bar for releasing said movable member.

36. In an automatic release mechanism, an automatic switch, means for controlling the same, and independently movable 60 guided member for releasing said controlling means and a pivoted latch bar controllable by the current supply for releasing said member.

In testimony whereof I have signed my 55 name to this specification in the presence of two subscribing witnesses.

ANTHONY J. BURNS.
